INVENTOR
BY Olaf Ekberg.
Attala G. Brown.
ATTORNEY

UNITED STATES PATENT OFFICE.

OLAF EKBERG, OF TOPEKA, KANSAS.

GARMENT.

Application filed March 18, 1922. Serial No. 544,839.

To all whom it may concern:

Be it known that I, OLAF EKBERG, a citizen of the United States, residing at Topeka, in the county of Shawnee and State 5 of Kansas, have invented certain new and useful Improvements in Garments; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to overcoats and particularly to the collars thereof.

The primary object of the invention is to provide a collar which may lay open with the lapels flat upon the breast in the 20 usual way, the collar being adapted to be buttoned up close about the neck when it is desired to use the coat as a storm coat or in cold weather.

Therefore, under ordinary conditions the 25 overcoat may have the appearance of an ordinary dress overcoat but in cold or stormy weather, the collar can be buttoned up close around the neck to give the appearance of a military overcoat and thereby 30 provide a storm collar.

The coat can be made for men or women while incorporating the principle of the invention.

In the drawings, 35 Fig. 1 is a front view of a coat with an open neck.

Fig. 2 is a similar view with the neck closed.

Fig. 3 is a plan view of the collar detached from the coat, and

Fig. 4 is a view of the collar folded over longitudinally.

The coat proper is designated 1 and may conform to any general style. The ends of 45 the collar 2 are slit, as at 3 and 4 and one end of the collar is preferably provided with buttonholes 5 and 6 while the other end of the collar on the inner side of the slit 3 is provided with a button 7, the button being 50 sewed on the underneath portion of the collar so that it will not be visible when the coat is open, as shown in Fig. 1.

The coat is provided with the usual lapels 8 and 9. When it is desired to wear the col-

lar in the usual way, as shown in Fig. 1, the 55 collar ends and lapels will appear as is common in an ordinary overcoat. When it is desired to use the coat as a storm coat, however, or to button the coat tightly around the neck, the lapels are folded one over the 60 other so that the lapel 9 comes within the lapel 8 and the buttonhole 10 can engage a button 11 normally concealed under the lapel 9. The buttonhole 6 will engage the button 7 so that the collar will take the 65 position shown in Fig. 2. If desired, the buttonhole 5 can also engage a button on the underside of the opposite end of the collar 2. The slits 3 and 4 permit the collar to be folded over or broken along the 70 line 12 (see Fig. 4) so that the portion 13 will fit tightly around the neck, allowing the portion 14 to lie comparatively loose so as to give a finished appearance to the coat.

75 It will be seen that the improvement in the coat is exceedingly simple in that it is only necessary to provide the slits 3 and 4, to divide the ends of the collar and provide the necessary buttonholes and buttons 80 in order to render the coat adaptable to two entirely different styles, one the open style as shown in Fig. 1, and the other the closed style as shown in Fig. 2.

What I claim and desire to secure by 85 Letters-Patent is:

1. A coat having a collar, the ends of which are separated from the lapels of the coat, the ends having longitudinal slits in their edges, and means for fastening the 90 ends of the collar together on the inner portions to leave the outer portions on the outside of the slits free to hang from the collar.

2. A coat having a collar and lapels, the 95 ends of the collar being spaced from the lapels and having longitudinal slits from their outer ends inwardly so that the collar is adapted in one position to lie flat against the shoulder and in another position to fold 100 along the lines of the slits, and means for fastening the inside of the collar portions together when the collar is folded along the line of the slits.

In testimony whereof I affix my signature.

OLAF EKBERG.
